UNITED STATES PATENT OFFICE.

JOHN NESBITT, OF COLUMBUS, OHIO.

DESIGN FOR A BICYCLE-STAND.

SPECIFICATION forming part of Design No. 25,878, dated August 4, 1896.

Application filed June 22, 1896. Serial No. 596,553. Term of patent 7 years.

To all whom it may concern:

Be it known that I, JOHN NESBITT, a citizen of the United States, residing at Columbus, in the county of Franklin and State of Ohio, have 5 invented and produced a new and original Design for Bicycle-Stands; and I do hereby declare the following to be a full, clear, and exact description of the same, reference being had to the accompanying drawing, forming a 10 part thereof.

The annexed illustration represents in perspective view an embodiment of my design. In the drawing, *a* designates the base board or piece, and *b* a piece extending crosswise of 15 the base. The head *d* of the stand consists of a U-shaped piece, which is supported by legs *e e e*, one of which extends from the head

to the base-board, while the others extend to the ends of the cross-piece *b*. On the front end of the base-board is a block or elevation *f*. 20

The main features of my design are the head-piece *d*, the legs *e* supporting the head-piece, and the recessed cross-piece *b* extending between the legs.

What I claim is—

25 The design for a bicycle-stand substantially as herein shown and described.

In testimony whereof I affix my signature in presence of two witnesses.

JOHN NESBITT.
